CLAIM

The ornamental design for a bottle sleeve, as shown and described.

DESCRIPTION

FIG. 1 is a top perspective view of a bottle sleeve showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a top perspective view of a bottle sleeve showing my new design, shown in an environmental subject matter;

FIG. 10 is a bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken line showing of a bottle is included for the purpose of illustrating environmental structure and forms no part of the claimed design.
